UNITED STATES PATENT OFFICE

HAROLD J. GOSS, OF NASHUA, NEW HAMPSHIRE, ASSIGNOR TO THE INTERNATIONAL PAPER BOX MACHINE COMPANY, OF NASHUA, NEW HAMPSHIRE, A CORPORATION OF MAINE

POWER-OPERATED COUNTER

Application filed June 16, 1928. Serial No. 286,009.

This invention relates to counting mechanism adapted to be attached to machines which make or treat such articles as blanks for the production of envelopes or paper boxes, and the invention has particular reference to that type of mechanism which effects counting of the articles by indicating to an attendant that a predetermined number (such as fifty) are ready to be picked up for boxing or laying aside in piles or groups.

One of the objects of the present invention is to provide an improved power-operated counting mechanism having friction rolls or disks both of which are positively driven and which so firmly grip passing articles as to effect lateral displacement of them at predetermined intervals even when the articles are of thin paper and consequently somewhat slippery.

Another object is to provide a counting mechanism which permits the articles to pass very freely, without having to exert any material pressure on any part of the mechanism to actuate such part.

With the above objects in view, and others hereinafter explained, the invention consists in the construction and combination of parts substantially as hereinafter described and claimed.

Of the accompanying drawings:

Figures 1 and 2 are side elevations of the counter, looking from opposite sides thereof.

Figure 3 represents a section on line 3—3 of Figure 1.

Figure 4 represents a section on line 4—4 of Figure 3.

Similar reference characters designate similar parts or features in all of the views.

All parts of the counting mechanism are carried by a single frame plate 12 having openings in suitable locations to enable the whole to be supported by and adjustable along tie rods of the machine to which said counting mechanism is attached. The different parts of the mechanism presently described are supported at opposite sides of the said single frame plate 12 and are therefore so exposed as to be easy of access for examination, cleaning, oiling, or repairing.

At one end of said frame plate 12 are upper and lower angular brackets 13 having bearings 14 for shafts 15. The lower bracket is fixed and the upper one is pivotally supported for a purpose hereinafter explained.

At one end the two shafts 15 have intermeshing gears 16, and the upper shaft has also a pulley 17. At the other end, each shaft has a roll or disk 18 having a frictional periphery.

Projecting from one side of the frame plate is a stud 19 which supports a pendant stem or rod 20 on which are idly mounted two pulleys 21 to properly guide a belt 22 which passes around the pulley 17 to drive the two disks 18. Said belt 22 is driven from any suitable shaft of the machine to which the counter is connected, but it is important, for a reason hereinafter explained, that the belt 22 shall be driven at such speed that the peripheral speed of the disks 18 which are operated by said belt shall exceed the speed of travel of the articles that are being delivered from the machine past the counter, by belts *b*, *b*, portions only of which are illustrated.

Extending through a bearing in the frame plate 12 is a shaft 23 which is constantly driven or rotated by gearing not necessary to illustrate, such gearing being provided by the machine to which the counter is attached. Said shaft and its cams presently described rotate once for each operation of the machine and its delivery. In other words such rotation is in synchronism with the timing of the passage of the articles effected by the belts *b*, *b*.

Secured to the shaft 23 at one side of the frame a plate is a cam 24 (Figs. 1, 3 and 4) on which bears a roll 25 carried by a lever 26 having a notched tip presenting a shoulder 27. Said lever is pivotally mounted on a shaft 28 rotatably mounted in the frame plate and having a ratchet wheel 29 secured thereto. The lever has a pawl 30 having a bevelled or inclined heel portion, the front tooth of said pawl engaging the ratchet wheel to actuate it and its shaft, a suitable detent pawl 31 being employed to prevent backward rotation of the ratchet.

wheel. A spring 32 connected with the rear end of the lever tends to depress the forward end or tip of the lever toward a stop 33 projecting from the frame plate.

5 A strip 34 mounted on a stud 35 projecting from the frame plate, below the lever, guides side portions of the blanks or other articles which are being delivered by belts *b*, *b*, from the folding or other machine to 10 which the counter is applied. Such articles move in the direction and about the plane of the arrow *a* in Figure 1. Portions of such belts are indicated in Figures 2 and 4. In practice said belts do not hold or grip 15 the articles so closely as to interfere with certain ones being directed laterally away from the said belts as hereinafter described, by the laterally inclined discs 18 having the higher speed of rotation.

20 Projecting from the guide strip 34 is a stop pin 36 to limit the downward position of a finger 37 projecting from a rocker 38 pivoted at 39 and having an upright pin 40 which coats with the notched tip of the 25 lever 26 as presently described. A spring 41 connecting the rocker with a fixed pin 42 tends to hold the rocker with its finger 37 in the position illustrated in Figure 1.

The upper bracket 13 which carries the 30 shaft of the upper displacing disk 18 is pivoted at 43 (Fig. 1) and has an arm 44 (Fig. 2) provided with a roll 45 at its end bearing against a cam 46 secured to the shaft 23 on the other side of the frame plate from 35 the cam 24. A spring 47 tends to hold the upper bracket with the roll 45 in contact with the cam 46.

The arm 44 has a tooth pin 48 adapted to cooperate as hereinafter described with a 40 notch 50 in the periphery of a disk 49 carried by the shaft which is rotated by the ratchet mechanism illustrated by Figure 1 and hereinbefore described.

45 Projecting from the disk 49 is a pin 51 to actuate the arm 52 of a Veeder or other well-known type of counting device indicated at 53, which device numerically exhibits the total of passed articles and therefore needs no illustration or description of 50 its structure, especially as such device forms no part of the present invention.

It will now be understood that each time 55 that the lever 26 is free, as presently described, to descend, the pawl 30 moves up and advances the ratchet wheel 29 one tooth. To prevent overthrow of the ratchet wheel I provide a stop screw 54 (Fig. 1) which is adjusted to such position that when the pawl 30 has just advanced the ratchet wheel 60 one tooth, the bevelled or inclined heel of said pawl contacts with the lower end of said screw 54 so that the pawl is momentarily locked in the space between two teeth of the ratchet wheel, so that said wheel can 65 not rotate farther until said pawl is re-

leased. Such release occurs as soon as the lever returns to the position illustrated in Figure 1.

The operation of the mechanism will now be described:

Normally the inter-geared and therefore positively rotated disks 18, 18, remain spaced slightly apart as illustrated by Figure 1, and when so spaced no articles passing between them will be deflected from a straight path of travel but will remain between the belts *b*, *b*, until delivered by the latter onto the usual travelling receiving platform that is customarily employed. Every article approaching the disks 18 70 passes over the guide strip 34 and while doing so causes the finger 37 to swing up. Said finger is at such an acute angle to the path of travel of the articles as to offer no appreciable resistance to the movements of the articles. It is to be borne in mind at this point that the lever 26 is being constantly actuated slightly by the cam 24 but can 75 actuate the ratchet wheel a tooth only when the finger 37 is lifted and the pin 40 swung 80 away from under the tip of the lever. Consequently if there is any interruption in the timed passage of the articles, there will be no actuation of the counter. But each article which does pass over the guide strip, 85 causes the finger to lift and the pin 40 to swing back, thereby releasing the lever 26 so that the low portion of the cam permits the outer end of the lever to drop and the other end to actuate the ratchet wheel. Then 90 the completion of the rotation of the cam lifts the lever so that the upright pin 40 can resume the position illustrated and then 95 there will be no further actuation of the ratchet wheel until another article passes 100 over the guide strip 34.

So long as the displacing disks 18, 18, remain apart, all of the passing articles will be deposited on the usual receiving belt or platform in a straight line, and all are 110 causing actuation of the ratchet wheel. The operation of the mechanism which closes the disks together will now be described.

Assuming that the ratchet wheel has fifty 115 teeth, the closing of the disks together must occur only once for the passing of each series of fifty articles. This occurs when the notch 50 in the disk 49 (Fig. 2), which disk of course is rotated by and with the ratchet wheel, arrives opposite the tooth 48 of the arm 44. Then when the low portion of the cam 46 next passes the roll 45 of the arm 44, the spring 47 acts to aid gravitation so 120 that the upper disk 18 is lowered into contact with, or sufficiently close to, the lower disk 18, with the result that the next passing article will be removed from between the carrier belts *b*, *b*, and be delivered out 125 of line with those previously delivered. To properly effect such lateral displacement it 130

is advantageous to have the peripheral speed of the two positively rotated disks 18 exceed the speed of travel of the belts b , b , as has been explained.

5 Owing to the fact that both of the disks 18 are positively rotated, they both, when closed together, instantly act on both surfaces of the blanks, and so firmly grip the latter that positive lateral displacement is effected even when the material of the blanks is very thin and so calendered or otherwise treated as to be of a slippery nature.

10 The article following the one displaced is not directed aside because, when it passes over the guide strip 34 it causes the finger 37 to rise and instantly permits the actuation of the ratchet wheel another tooth in the manner that has been explained. And 15 since the notched disk 49 rotates with the ratchet wheel, its notch 50 is moved beyond the pin 48 of the arm 44. This will be clear when it is understood that the cam 46 and spring 47 are constantly causing a slight 20 rocking of the arm 44, but that the lowering of the upper disk close to the lower disk can occur only when the notch 50 of the disk 49 is opposite the tooth or pin 48 of the arm 44.

25 The cam 46 performs the additional function of preventing the tooth pin 48 from acting as a retard on the periphery of the disk 49 and wearing it, as will now be explained.

30 The high portion of the constantly rotating cam 46 acts on the roll 45 of the arm 44 to prevent contact of the tooth pin 48 with the periphery of the disk 49 just as and while the said disk is being given a rotative 35 impulse by the operation of the ratchet mechanism. Mere tapping contact of the tooth pin with the disk does no harm. But when the notch 50 of said disk arrives opposite the tooth pin the latter enters the notch so that when the low portion of the cam 46 passes the roll 45 of the arm 44, the disks 18 are free to act on the passing 40 article to direct it aside as has been explained. The immediate next removal of the tooth pin from said notch due to the further rotation of the cam 46 permits the next step of rotation of the disk 49 due to the next actuation of the ratchet mechanism.

45 The advantages of the structure including the notched disk 49 and tooth pin 48 will be clearer when it is understood that the cam 46 (Fig. 2) which rotates once for each passing blank, is constantly effecting a rocking of the arm 44 to a degree limited by the rocking and tapping contact of the pin 48 against the periphery of the disk 49, which limitation prevents complete lowering of the upper disk 18. But when 50 the notch 50 in the disk 49 arrives oppo-

site the pin 48, the very next rotation of the cam 46 permits the instant movement of the pin into the notch and a consequent quick closing together of the displacing disks 18 both of which are positively rotated.

55 The timing of operation of the parts of the mechanism is such that just before an article reaches the guide strip 34, the cam 24 lifts the lever 26 enough so that the upright pin 40 is free from any pressure by said lever, and consequently the article passing over the guide strip easily lifts the finger 37 and therefore swings the pin 40 back or away from the tip of the lever, so 60 that the low part of said cam can permit the lever to drop and result in the actuation of the ratchet mechanism. The passing article therefore is not required to exert any pressure on anything to directly effect 65 a counting operation. After a passing article has lifted and then passed the finger, and has been counted, the finger drops again, and when the lever is lifted by the next rotation of the cam 24, the upright 70 pin 40 regains the position shown in Figure 1. Therefore, although the cam is rotated in synchronism with the planned timing of the passing articles, any interruption in the regularity of the succession of passing articles simply leaves the counting mechanism idle. In other words, there can be no operation of the ratchet mechanism when there is any skip in the succession of passing articles, in spite of the fact that the 75 shaft 23, with its two cams 24 and 46, and both of the disks 18, 18, are constantly and positively driven.

80 Having now described my invention, I claim:

1. A counter having a pair of angularly mounted normally separated friction disks, means for positively rotating both of them, and means for bringing said disks close together momentarily when one of a predetermined number of moving articles reaches 85 position to be grasped by said disks.

100 2. A counter having upper and lower angularly mounted shafts provided with friction disks and intermeshing gears, means for positively driving said shafts, the upper shaft being movable toward and from the lower shaft, means for holding the upper shaft normally raised, and means for permitting lowering of the upper shaft when 105 one of a predetermined number of moving articles reaches position to be grasped by said disks.

110 3. In a counter having a frame plate, a shaft mounted in and extending through said plate, cams carried by said shaft at opposite sides of said plate, a ratchet mechanism on one side of the plate operated by one of the cams, and means located at the other side of said frame plate and controlled 115

by the other cam for effecting displacement of one of a predetermined number of passing articles.

4. In a counter having a frame plate, a shaft mounted in and extending through said plate, a ratchet wheel and notched disk carried by said shaft at opposite sides of said plate, means controlled by a succession of passing articles for actuating said ratchet wheel and its shaft, and means controlled by said notched disk for effecting lateral displacement of passing articles at predetermined intervals.

5. A counter having a ratchet-controlled mechanism for effecting displacement of passing articles at predetermined intervals, a lever having a shoulder at its tip and provided with a ratchet-operating pawl, a cam for operating said lever, and a rocker having a pin to engage said shouldered tip of the lever, said rocker having a finger extending across the path of the passing articles.

6. A counter having a guide for a succession of passing articles, a pivoted finger movable to and from a position crossing the plane of said guide at an acute angle relatively thereto, normally inactive ratchet driven counting mechanism, and power-operated means controlled by said finger for effecting operation of the counting mechanism when the finger is shifted by a passing article.

7. A counter having a guide for a succession of passing articles, a pivoted finger movable to and from a position crossing the plane of said guide at an acute angle relatively thereto, a ratchet-operated counting mechanism, a power-operated cam, a lever, a ratchet-operating pawl carried by said lever, and means controlled by said finger for permitting the said lever to be actuated by said cam.

8. A counter having a pair of normally separated friction disks positioned relatively to the path of travel of a succession of passing articles to effect displacement of some of the articles out of such path when said disks are in closed relationship, a notched disk, means controlled by the passing articles for effecting rotation of said notched disk, and a movable member for permitting and preventing closing of said friction disks together, said movable member having a tooth cooperating with the notched disk to permit closing of the friction disks together at predetermined intervals.

9. A counter having a fixed bearing and a movable bearing, shafts in said bearings and having friction disks positioned relatively to the path of travel of a succession of articles to effect displacement of some of the articles out of such path, the movable bearing having a toothed arm, a cam and spring for effecting oscillations of the movable bearing and its toothed arm, a notched

disk cooperating with the toothed arm to prevent and to then permit movement of the latter at predetermined intervals, and means controlled by the passing articles for effecting rotation of said notched disk.

10. A counter having mechanism for effecting displacement of passing articles at predetermined intervals, said mechanism including a power-driven shaft carrying a cam, a ratchet wheel, a lever actuated by said cam and having a ratchet-wheel-actuating pawl, and means for holding said pawl in locking engagement with the ratchet wheel while said pawl is at the extreme of its actuating movement.

11. A counter having mechanism for effecting displacement of passing articles at predetermined intervals, said mechanism including a power-driven shaft carrying a cam, a ratchet wheel, a lever actuated by said cam, a pawl carried by said lever for actuating the ratchet wheel, said pawl having a bevelled heel, and a stop in position to contact with the bevelled heel of the pawl when said pawl is at the extreme of its actuating movement to temporarily lock the said pawl in engagement with the ratchet wheel.

In testimony whereof I have affixed my signature.

HAROLD J. GOSS.
